UNITED STATES PATENT OFFICE.

FRANK V. CARMAN, OF OAKLAND, CALIFORNIA.

RAIL-PROFILE INSTRUMENT.

1,347,078.

Specification of Letters Patent.

Patented July 20, 1920.

Application filed September 16, 1919. Serial No. 324,122.

To all whom it may concern:

Be it known that I, FRANK V. CARMAN, a citizen of the United States, residing at the city of Oakland, in the county of Alameda and State of California, have invented certain new and useful Improvements in Rail-Profile Instruments, of which the following is a specification.

My invention relates to an instrument 10 for measuring a rail by making an outline of its cross-section contour, or profile.

My invention is particularly adapted for measuring railway rails, although it may be used upon any similar beam or rail.

15 In railway practice it is necessary to replace a rail, for the sake of safety, when the cross-sectional area of its head is reduced, by wear, to a certain predetermined fraction of its original value. This wear is

20 customarily measured by making a plaster cast of the worn rail, while still in place in the track, and then making a profile drawing from said plaster cast, and comparing it with a standard profile of the unworn rail.

25 This involves considerable time and labor, in making the cast, removing it from the rail, transporting it to drafting room, and drawing the profile.

The object of my invention is to provide 30 an instrument by means of which an accurate profile of a rail may be quickly and easily made in one operation, the instrument being attached to the rail to be measured, and the profile drawn directly therefrom, 35 either upon a blank sheet or superimposed upon a previously prepared profile of the standard rail, so the comparison may be easily and accurately made at once.

My invention will be more fully described 40 with reference to the accompanying drawings, wherein;

Figure 1 is a front elevation of my rail profile instrument.

Fig. 2 is a rear elevation of the same.

45 Fig. 3 is a vertical transverse section on the line 3—3 of Fig. 2 looking in the direction of the arrows.

Fig. 4 is a partly broken view, enlarged, of the stylus and its supporting arm.

50 Fig. 5 is a detailed view, enlarged, of the carriage retaining latch.

Referring more particularly to the drawings, the reference numeral 1 designates a rail of which the profile is desired. A pair

of parallel vertical clamping members 2, 55 Figs. 1 and 2 provided with feet 3 adapted to embrace the base flange of the rail, are operated by right- and left-threaded screws 4 Figs. 2 and 3, passing through nuts 4', indicated by dotted lines in said clamping 60 members. Said screws are provided at their center portions with sprockets 6, which are connected by a chain 7, so as to operate in unison, and one of said screws is further provided with a handle 8, Figs. 1 and 2, said 65 handle being preferably removable.

The screws 4 are journaled in brackets 9, Fig. 2, projecting from the back of a plate 10, which is held in a vertical position above and at right-angles to the rail to be measured.

The plate 10 has on its front surface a holder 11 Fig. 1, in which may be placed the paper, card or sheet 12 on which the profile is to be drawn. This holder consists of 75 three strips, one at bottom and one at each side, as shown in Fig. 1, secured to the plate 10, and overlapping the bottom and side edges of the paper 12. At the upper and lower edges of the plate 10 Fig. 1 are horizontal slotted guides 13, in which operate sliding members 14. The slotted guides 13 are, as shown in Fig. 3, tubular, and the sliding members 14 are correspondingly cylindrical, though these shapes, while affording accuracy of movement, are not essential. These sliding members are connected by a vertical slotted or channeled guide 15, and braced thereto by diagonal members 16.

A vertical slide 17 Figs. 1 and 3, operates 90 within the channel of the vertical guide 15, and is provided with an operating handle 18.

At its lower end said slide 17 carries a double finger 19 adapted to be moved over and follow the surface or contour of the rail 95 1.

Near its upper end, the slide 17 carries a horizontally disposed reversible arm 20, secured preferably by a knurled nut 21 and located or fixed by dowel pins 22, so that said arm may be moved to extend to either 100 side of said slide 17.

At the end of the arm 20 is carried a stylus 23, Fig. 1, which is illustrated in its preferred form in Fig. 4 as a pencil holder comprising a tube 24 adapted to contain a pencil 105 25, a conical cap 26 having a central opening through which the point 27 of said pencil projects, a spring 28 for forcing said

pencil outwardly, an adjusting screw 29 for regulating the tension of said spring, and a removable protecting shell 30.

At the upper end of the vertical slide 17 there is provided a latch 31, Figs. 1, 3 and 5, rotatably secured to said slide, and having its end portion bent horizontally, as shown. Said latch 31, when swung into register with the slot or channel in the vertical guide 15, as shown in Figs. 1 and 3, operates within said slot, permitting free vertical movement of the slide 17, and when swung to a position to engage the upper end of said guide 15, as in Fig. 5, said latch supports the slide 17 and prevents it from dropping; and in order to keep said slide 17 from falling entirely out of its guide 15 there is provided a stop 32, Figs. 1 and 3, secured to said slide at 33, and adapted to abut against the lower support 34 of said guide 15, Fig. 3.

The clamping members 2 are provided with pockets 35, Fig. 2 in which may be carried the removable stylus 23 and the removable clamp-screws-handle 8 when the instrument is not in use. Likewise shims 36 may be carried in said pockets, said shims being provided for insertion between the base of the rail 1 and one of the clamp feet 3, as shown in Figs. 1 and 2, for the purpose of truing the instrument in case it is desired to draw the rail profile upon a standard profile previously drawn upon the sheet, in order to compare the two.

In the operation, the instrument is first clamped upon the rail 1 whose profile is desired. The stylus 23 is then placed in position, and the latch 28 moved into register with the slot of the vertical guide 15. The operator then moves one of the fingers 19 over the cross sectional contour surface of the head and web of the rail upon one side, the pencil tracing and duplicating a corresponding line upon the sheet. The stylus is then reversed to extend in the opposite direction, and the other finger 19 is caused to follow the contour surface of the other side of the rail, thus completing an accurate and full-size profile of the rail.

In this operation, it will be seen that by reason of the horizontally sliding members 13 with their connecting guide 15, and the vertically movable slide 17 in said guide, which said parts constitute, in effect, a carriage mounted for universal movement in a plane, the contour following fingers and the stylus associated with said carriage are enabled to execute duplicate movements.

I claim:

1. A rail profile-drawing instrument comprising a paper-holder; clamping members for securing said paper-holder to the rail in a plane perpendicular thereto; a horizontal guide at the top and bottom of said paper-holder; a slide member in each horizontal guide; a vertical guide connecting said slide members; a slide operating within said vertical guide; a stylus carried by the upper portion of said slide and adapted to be extended laterally

said slide members; a slide operating within said vertical guide; a stylus carried by the upper portion of said slide; and a finger secured to the lower portion of said slide and adapted to follow the surface of said rail.

2. A rail profile-drawing instrument comprising a paper-holder; clamping members for securing said paper-holder to the rail in a plane perpendicular thereto; a horizontal guide supported by said paper-holder; a vertical guide movably mounted within said horizontal guide; a slide operating within said vertical guide; a stylus carried by said slide and adapted to be extended laterally in either direction therefrom; and a pair of oppositely disposed laterally projecting fingers secured to said slide adapted to follow the surface of said rail.

3. A rail profile-drawing instrument comprising a paper-holder; clamping members for securing said paper-holder to the rail in a plane perpendicular thereto; a horizontal guide at the top and bottom of said paper-holder; a slide member in each horizontal guide; a vertical guide connecting said slide members; a slide operating within said vertical guide; a stylus carried by the upper portion of said slide and adapted to be extended laterally therefrom in either direction; and a pair of oppositely disposed laterally projecting fingers carried by the lower end of said slide, one adapted to follow the surface of the rail on one side and the other to follow the surface on the other side.

4. A rail profile-drawing instrument comprising a paper-holder; a pair of co-acting members carried by the paper-holder and adapted to clamp the base of the rail to hold the paper holder in a plane perpendicular to the rail; screws carried by the paper-holder and engaging said members to clamp them to the rail base; guides supported by said paper-holder; a movable carriage operating within said guides; a stylus mounted on said carriage; and a finger secured to said carriage and adapted to follow the surface of said rail.

5. A rail profile drawing instrument comprising a paper-holder; a pair of co-acting members carried by the paper-holder and adapted to clamp the base of the rail to hold the paper holder in a plane perpendicular to the rail; a pair of screws carried by the paper-holder and engaging said members to clamp them to the rail base; a chain connecting said screws to effect their operation in unison; a horizontal guide at the top and bottom of said paper-holder; a slide member in each horizontal guide; a vertical guide connecting said slide members; a slide operating within said vertical guide; a stylus carried by the upper portion of said slide and adapted to be extended laterally

therefrom in either direction; and a pair of oppositely disposed laterally projecting fingers carried by the lower end of said slide, one adapted to follow the surface of the rail on one side and the other to follow the surface on the other side.

5 In testimony whereof I have signed my

name to this specification in the presence of two subscribing witnesses.

FRANK V. CARMAN.
